UNITED STATES PATENT OFFICE.

FRANCIS C. PETERSON, OF EVERETT, WASHINGTON, ASSIGNEE TO PETERSON & NETHAWAY, OF EVERETT, WASHINGTON, A CORPORATION.

ROTARY PUMP.

Application filed January 15, 1927. Serial No. 161,352.

The present invention relates to rotary pumps designed to pump either gas or liquid.

Generally, the pump comprises a cylindrical shell or casing having an inlet and an outlet and containing an eccentrically mounted cylindrical rotor with three or more isolating vanes, blades, or impellers. These impellers are carried on axle and wheel assemblies and are actuated in and out of the revolving piston by a tension ring centralized in the revolving piston thereby causing a positive action.

Provision is made for wear on the shell at the point of the contact with the piston between the intake and outlet by using a rectangular strip inserted in the shell and adjusted by set screws or the like.

Provision is also made for efficient lubrication of the wheel and axle assemblies and the blades or impellers.

The device is comparatively simple in its construction, thoroughly efficient and reliable in its operation and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:—

Figure 1 is a side elevation of the pump embodying the features of this invention,

Fig. 2 is an end elevation thereof showing one of the cylinder heads removed and a portion of the shell or casing in section,

Fig. 3 is a vertical section taken substantially on the line 3—3 of Fig. 1 looking in the direction of the arrows,

Fig. 4 is a vertical section taken substantially on the line 4—4 of Fig. 3,

Fig. 5 is a perspective view of the tension ring,

Fig. 6 is a perspective view of one of the blades or impellers,

Fig. 7 is a perspective view of one of the wire strips.

Referring to the drawings in detail it will be seen that 5 denotes a cylindrical stator casing or shell having an outlet 6 and an inlet 7. The outlet and inlet are disposed tangentially to the axis of the casing or shell

and the former is at the top thereof and the

latter at the bottom. This cylindrical stator casing or shell 5 is preferably mounted on a suitable supporting or pedestal structure 8 and has cylinder heads 9 and 10 which are provided with eccentric openings or bearings 60 for rotatably receiving a shaft 11 which will be driven in any suitable manner. On this shaft 11 and keyed thereto within the cylindrical stator casing or shell 5 is the rotor or cylindrical piston 12 having peripheral compartments 14, the bottoms or inner surfaces of which are curved on arcs eccentric to the periphery of the cylindrical stator casing or shell 5 and have arcuate end walls 15 and arcuate end walls 16, the latter being 70 longer than the former and at the inner ends of the bottom surfaces and curved on larger radii. Spiders 13 are of circular formation and are provided with central openings 18 through which the shaft 11 projects and the 75 peripheries thereof are disposed coincident with the periphery of the piston 12. These spiders 13 are provided with peripheral notches 20, the inner ends of which are arcuately curved. Axe pins 21 have wheels 80 22 journaled on their ends. These axe pins 21 extend through bores 23 provided in impellers or piston blades 24 which are shaped to fill the compartments 14. The blades or impellers 24 are provided with eccentric 85 outer curved surfaces 25 in relation to inner curved surfaces 26 and edge curved surfaces 27 and 28 respectively, the latter edge surface being smaller than the former. The bores 23 are disposed adjacent the inner 90 corners of the impellers 24 adjacent the edges 27 thereof. The wheels 22 are adapted to ride or bear on the interior surface of the cylindrical stator casing or shell 5 and to move in the notches 20. The spiders 13 are 95 held in place one on each side of the rotor or piston 12.

A wear and seal strip 33 is disposed in a recess 34 and is adjusted by means of set screws 35. The recess 34 is located between 100 the inlet 7 and the outlet 6. It is to be noted that the shaft 11 in its eccentric mounting in the cylindrical stator casing or shell 5 is disposed towards the inlet and outlet sides of the casing or shell, that is, is 105 located closer to the wear and seal plate 33 than to the opposite diametric point of the casing or shell 5.

When the parts are assembled as is shown in Figs. 2 and 3 to advantage, and the shaft 11

is rotated in a counter-clockwise direction, the impellers or blades are disposed as shown, that is, the bottom impeller will be disposed outwardly of the lowermost compartment 5 and therefore this compartment will fill with gas or liquid from the inlet 7 and as the piston rotates it will be seen that said impeller is forced into the compartment particularly by engagement with the wear 10 and seal plate 33 so as to force the fluid or air out through the outlet 6, thus a pumping action is set up. A priming plug is shown at 40 at the top of the casing or shell 5 as the casing or shell must be filled with fluid in its 15 initial operation if it is to be used for pumping fluid. The wheels rise on the interior surface of the cylindrical stator casing or shell 5 thus minimizing friction and wear and assuring proper operation of the impellers.

In order to positively urge the impellers or blades outwardly from the compartments 14 I construct the piston 12 in two parts as is clearly shown in Fig. 4 and form between 20 the parts thereof an annular recess 41 concentric about the shaft 11 and entering the bottoms or inner portions of the compartments 14 as is clearly indicated in Figs. 2, 3 and 4. A split tension ring 42 is disposed in 25 the recess 41 and engages the surfaces 26 of the impellers 24 as is illustrated in Fig. 3 for urging the two impellers 24 remote from the wear strip 34. That is, as one of the impellers engages the wear strip to be forced into its compartment the other impellers are 30 positively thrust out of their compartments. Thus it will be seen that the split ring has a floating mounting in the recess 41. In each compartment 14 in the wall 16 thereof, there 35 is provided a pocket for receiving a wear strip 44 engageable with the edge curved surface 27 of the impeller 24 located therein. In the outer surface 25 of each impeller 24 there is formed a pocket 45 adjacent edge 27 for receiving wear strips 46 to engage the 40 interior periphery of the shell or casing 5. It is to be noted that these wear strips 46 are the only portions of the impellers that engage the shell 5. Thus practically all the 45 wear of this pump is taken care of by the wear strips 34, 44, and 46 which may be replaced.

The shaft 14 has a longitudinally extending bore 48 extending inwardly from the 50 end adjacent the cylinder head 10. This cylinder head is provided with an opening 49 registering with the bore 48 so that suitable communication may be made with a source of lubricant supply. The bore 48

terminates in a diametrically extending 60 passage 50 entering annular groove 51 on the periphery of the shaft 11 within one part of the piston 12. Said part of the piston 12 is provided with three radiating oil passages 52 the inner ends of which register with the 65 groove 51 and the outer ends of which are closed by plugs 53. Said part of the piston 12 is further provided with passages 54 connected with the outer ends of the passages 52 to lead the oil to end walls 15 of pockets 70 14.

Each impeller or blade 24 is provided with a longitudinally extending oil passage 55 one end of which is adapted to register with the passage 54 and the other end terminates 75 in the edge 27. The passage 55 communicates intermediate its ends with the bore 23 for lubricating the axle 21.

The numerous advantages of this pump constructed in accordance with the foregoing 80 will be perfectly clear without further explanation or description and it will also be obvious that the pump will operate efficiently for the purposes desired. While the present embodiment of the invention has been 85 disclosed in detail, it is apparent that this disclosure is merely by way of example since in actual practice this embodiment attains the features of advantage enumerated as desirable in the statement of the invention and 90 the above description. Numerous changes, however, in the details of construction and in the combination and arrangement of parts may be resorted to without departing from the spirit or scope of the invention as hereinafter claimed or sacrificing any of its advantages. Having thus described my invention, what I claim as new is:—

In a pump, a cylindrical stator casing having an outlet and an inlet tangentially disposed to its axis, cylinder heads for the casing, a cylindrical piston in the casing, means for rotatably mounting the piston eccentrically in the casing, said piston having peripheral compartments, impellers mounted 100 in said compartments, spiders one on each end of the piston and having peripheral pockets, an axle rotatably mounted in each impeller, wheels on the axles, one in each pocket, said piston being formed in two complementary sections the abutting faces of which are formed with annular recesses entering the compartments, and a floating split 105 spring ring in the recesses and engaging the impellers to maintain the wheels in contact 110 with the interior of the casing.

In testimony whereof I affix my signature.
FRANCIS C. PETERSON.
